STORAGE AND DISPENSING APPARATUS

Christian L. Hansen, Pewaukee, Wis.

Application October 27, 1941, Serial No. 416,681

5 Claims. (Cl. 221—67)

This invention relates to improvements in storage and dispensing apparatus adapted for the bulk storage and convenient use of gasoline, other liquid fuels, or the like.

Farmers, and others in rural sections of the country, find it desirable to purchase gasoline or the like in barrels because of the lower cost when purchased in bulk, and also to insure having an adequate supply of fuel on hand. While this practice is desirable and satisfactory in the summer, and in other times of the seasons of the year when rapid changes in temperature are not experienced, it is not practical or satisfactory in winter, or when a wide variation in temperature occurs, for the reason that when the barrel is only partially full, the moisture suspended in the air within the barrel and above the surface of the fuel will condense or collect on the exposed inner surfaces of the barrel above the liquid fuel level when the barrel becomes chilled upon a sudden drop in temperature. During the day when the sun is shining and the air is warm, and liquid fuel is dispensed from the barrel, the air that flows in the top of the barrel, as the liquid flows out, will contain a considerable amount of suspended moisture, and then, in the evening or at night, when the temperature drops and the barrel becomes chilled, this moisture will collect or condense on the exposed inner surfaces of the barrel and will find its way into the fuel. This difficulty obtains not only on farms and in rural areas but also in various kinds of field work, such as road building, excavating, threshing, and all kinds of out-door type of work where it is a practical necessity to have a bulk supply of motor or burner fuel on the location where the operation is being carried out. Of course, this problem does not obtain where it is feasible to employ underground tanks, but such tanks and their installation are expensive and require pumps for dispensing the liquid therefrom.

The object of the present invention is to provide a storage and dispensing apparatus which will prevent condensation or deposit of moisture on the inner wall of the tank or receptacle containing the liquid fuel, which will facilitate dispensing of the fuel, which will eliminate or minimize fire or explosion hazards, which will provide a storage space for smaller dispensing containers, such as filling cans or the like, which will automatically dissipate any fumes from such storage space or from other parts of the apparatus, and which is simple and durable in construction, reliable, efficient and safe in use, and easy and

comparatively inexpensive to manufacture and install.

The apparatus is designed and adapted for outside installation at any convenient location, and while insuring the provision of a bulk supply of liquid fuel will preclude the condensation of the moisture in the walls of the tank or receptacle containing the fuel, thereby preserving the structural integrity of the receptacle, inasmuch as rusting thereof is prevented, and also precluding faulty carburization of the fuel by preventing a mixture of water therewith.

Other objects and advantages reside in certain novel features of the construction, arrangement, and combination of parts which will be herein-after more fully described and particularly pointed out in the appended claims, reference being had to the accompanying drawing forming a part of this specification, and in which:

20 Figure 1 is a perspective view showing a storage and dispensing apparatus embodying the present invention;

25 Figure 2 is a view thereof in transverse vertical cross section taken on line 2—2 of Figure 3 and with parts shown in elevation for the sake of illustration;

30 Figure 3 is a fragmentary view in bottom plan of the apparatus illustrated in Figures 1 and 2, parts being broken away and parts being shown in horizontal cross section for the sake of illustration; and

35 Figures 4 and 5 are views in vertical cross section illustrating the construction of the valve outlet fitting and showing the same in closed and open position, respectively.

40 Referring to the drawing it will be seen that a storage and dispensing apparatus embodying the present invention comprises an outer housing designated generally at 10, an inner receptacle 45 or tank designated generally at 11, and disposed within the housing 10, an outlet fitting designated generally at 12 at the bottom of the tank or receptacle 11 and connected to a dispensing hose 13 having a conventional valved nozzle 14 at its outer end.

45 The housing 10 includes a vertically disposed cylindrical body portion 15 preferably constituted of corrugated sheet metal of appropriate heavy gauge. An angle iron base ring 16 is interfitted with and suitably secured to the margin of the lower end of the body portion 15, the vertical flange of the angle iron ring 16 being engaged with the crests of the inwardly directed corrugations of the body portion 15 while the horizontal flange of the angle iron projects out-

wardly beyond the outer confines of the body portion. When the apparatus is installed the angle iron ring 16 is spaced slightly from the surface of a suitable foundation 17, which may be constructed of concrete by the feet 48. Bolts 19 are embedded in the concrete foundation 17, the shanks of the bolts extending up through the apertures of the feet 48 and having nuts 20 threaded thereon. This arrangement not only provides for the firm bolting of the apparatus to its foundation but electrically grounds the structure and provides for drainage of the compartment 50 as well as providing space for admission of air thereto. A domed top or roof 21 is provided for the upper end of the housing and is also constituted of sheet metal of appropriate gauge. In the construction illustrated, the roof 21 is circular or disc-like in form and it is securely assembled with the housing by means of a connecting angle iron ring 22 which has its vertical flange fitted within and secured to the upper end of the housing, and which has its horizontal flange underlying the top or roof adjacent its periphery and secured thereto by screws or other suitable fastening devices 23. The top or roof is of greater diameter than the housing so that the outer marginal portion thereof overhangs the outer periphery of the housing. At its center the roof or top 21 is provided with an opening 24. A hood or cowl 25 is assembled with the opening 24 and is constructed to facilitate the exit of fumes or gases and air from the interior of the housing 10 while preventing the ingress of moisture, dust, rain, snow, or the like, into the interior of the housing through the opening at the top.

The housing 10 is provided at one place in its periphery with a vertical door opening, designated generally at 38, the housing being cut away to provide a door opening, and the vertical edges of the door opening being doubled upon themselves or are otherwise suitably reinforced to stiffen and strengthen them and are also outturned so as to present outturned doubled flange formations which constitute the jambs or side posts of the doorway. A door 32 is provided for the doorway and preferably comprises a body portion 33 constituted of corrugated sheet metal similar in structure to the sheet metal which makes up the housing proper. The door is suitably framed and this may be accomplished by folding or doubling vertical side edge portions of the door, as indicated at 34, and by welding or otherwise securing to the upper and lower edges thereof transverse metal frame pieces 35. Hinges 36 pivotally support one side of the door on the housing. When the door is closed it may be releasably secured in closed position by any suitable lock or fastener which is here illustrated for purposes of illustration, as the keeper 36 secured to the housing and a hasp 37 pivoted on the door and designed to fit over the staple of the keeper and to be secured in such position by a padlock or any suitable lock (not shown).

The inner tank or receptacle 11 is smaller than the housing. Usually it will be constructed of plain or galvanized sheet steel having a suitable capacity, such as a 110 gallon or two barrel capacity, or perhaps even a greater or lesser capacity. The tank 11 comprises a cylindrical body portion 40 equipped with upper and lower end heads 41 and 42. These end heads may be seamed to the ends of the body portion in any suitable way. For example, a seam, such as the seam 43 illustrated as connecting the lower end

head to the body of the tank, may be employed for both end heads, although it is also feasible to have one of the end heads, for example the upper end head 41, of cupped formation and inset and welded to the body portion, or may even be integral therewith. The inner tank or receptacle is supported within the housing by means of a supporting ring 44 of angle iron, the ring having its vertical flange secured to the crests of the inwardly directed corrugations of the body portion of the housing, if desired, and having its horizontal flange engaging the peripheral portion of the bottom of the tank of the receptacle 11. A very rigid and secure support for the ring 44 may be had by providing a suitable number of supporting legs 45. These legs 45, which may be constituted of channel irons, are disposed vertically and are located at spaced angular intervals within the housing. The legs 45 are secured by bolts and nuts 46 and 47 to the supporting ring 44 and base ring 16, respectively. Furthermore, the lower ends of the channel iron legs may be flattened out and outturned to provide supporting feet 48 directly engaging the foundation. With this construction it will be seen that the bottom of the inner receptacle is disposed at a substantial distance above the bottom of the housing, thereby providing a compartment 50 for the reception of gasoline dispensing cans and other similar paraphernalia. The upper end head 41 of the tank of the receptacle is provided with a removable filling plug and with a vent fitting 52 which may be suitably valved, if desired, and the top or roof 21 is provided with an opening 53 above the filling plug 51 to provide for access thereto. A hinged lid or closure 54 is provided for the opening 53.

At the center of the lower end head 42 an outlet opening 55 is provided. An outlet fitting 56 is applied to the bottom of the end head 42 around the outlet opening and may be welded in place. An elbow 57 is threaded into this outlet fitting and is connected by suitable pipe fittings 58, 59, to an outlet valve 60. The casing 61 of this valve receives the valve plug 62 which is of the type having axial and radial ports or passages, the axial passage having a nipple 63 connected therewith to facilitate the connection of the valve with the dispensing hose 13. When the nipple 63 is moved to its vertical position, as shown in Figure 4, the ports are disconnected and the valve closed. When it is moved to its horizontal position, as shown in Figure 5, the ports are in alignment and the valve is opened. To close the valve after using, it is only necessary to move the hose 13 up along the side of the tank 11, as shown in Figure 1. This automatically raises the nipple 63 to its vertical position and closes the valve 62. The door 32 is then closed and it holds the hose 13 in the vertical position. When it is desired to drain fluid from the tank, the door is opened and the hose 13 moved to substantially horizontal position. This moves the nipple 63 to its horizontal position, opening the valve. Flow can then be controlled by the hand nozzle 14.

In this construction it will be noted that there is a stack 70 surrounding the inner tank or receptacle 11 and completely enclosed by the corrugated metal housing in its door when the door is shut. At its upper end this stack 70 is in open and free communication with the enclosed air space or compartment 71 provided between the roof or top 21 and the upper end 41 of the tank,

and this air space and compartment 71 in turn freely communicates with the atmosphere through the cowl 26. The lower end of the stack 70 communicates with the compartment 50 through a multiplicity of air inlet or openings 75 defined between the vertical flange of the supporting ring 44 and the outwardly directed corrugations of the housing. Compartment 50 communicates from the outside between the ring 16 and top of the foundation. With the apparatus so constructed, air under the influence of convection currents or natural draft constantly flows into the compartment 50 through this space and then from the compartment 50 through the air inlet passages 75 to the stack 70, up through stack 70 around the tank or receptacle 11 into the compartment 71 and thence through the cowl 26 to the atmosphere. The housing not only encloses and protects the tank against the weather, but serves as a screen or shield to protect it from the radiant heat of the sun. It also is constituted as an element of the means which provides the ventilating stack 70 insuring continuous circulation of the air up and around the tank 11 under the influence of convection currents or natural draft to maintain a minimum differential between the temperature of the air within the tank and above the liquid therein, and the temperature of the outside air. As the outside air flows into the tank every time liquid fuel is drawn therefrom, it is obvious that by minimizing the differential between the two temperatures condensation or collection of moisture particles or drops on the exposed inner surfaces of the tank or receptacle will be precluded. Furthermore, the ventilating stack effect of the structure absorbs and dissipates fumes of spilled or overflowing gasoline and the fumes from the gasoline filling tanks stored in the bottom compartment. The air which is present in the stack 70 functions as an insulating shield or barrier which prevents radiant heat from reaching the metal of the inner tank. In the construction described, the air in the stack 70 has three functions, the insulating function just referred to, the part it takes in absorbing and dissipating fumes or gases, and its action in carrying off heat from the stack. The door of the outer housing coacts with the dispensing pipe to maintain it in position where the outlet valve is closed, and in a practical manner it insures proper positioning of the dispensing pipe and its nozzle when the same are not in use.

In many instances the air leakage through the door provides sufficient circulation. However, if desirable, a suitable number of properly sized air intake openings may be formed in the outer housing a proper distance above the base ring.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. A bulk storage apparatus for liquid fuel comprising an inner metallic tank for containing liquid fuel, a metallic housing enclosing and surrounding the tank in spaced relation thereto and coacting therewith to provide a stack along and around the tank, a cowl at the upper end of the housing cooperating with the stack to provide for

flow of air along and around the tank under the influence of convection currents, said tank being disposed in the housing with its lower end in spaced relation to the bottom thereof to provide a storage compartment for oil filling cans and the like, an outlet valve at the bottom of said tank, said valve having a nipple movable to a vertical position to close said valve, a flexible hose connected to said nipple for dispensing liquid from said tank, said housing having a door to provide for access to the compartment and for operative extension of said flexible hose, releasable fastening means for securing the door in closed position, said door when closed coacting with the flexible hose to retain the same in vertical position in the stack to maintain said nipple in vertical position and said valve closed.

2. A bulk storage and dispensing apparatus comprising an inner metallic tank for containing liquid fuel, an outer metallic housing enclosing and surrounding the tank in spaced relation thereto and coacting therewith to provide a stack along and around the tank, a cowl at the upper end of the housing and in cooperative relation to the stack to provide for flow of air through the stack under the influence of natural draft, said housing having a door extending the full height thereof to provide for access to the tank, and valve means for dispensing the liquid fuel from the tank which can be opened only when the door is open and must be closed to close the door.

3. A bulk storage and dispensing apparatus of the character described comprising an inner metallic tank made up of the cylindrical body portion and end heads secured and hermetically sealed thereto, an outer metallic housing surrounding and enclosing the tank and comprising a cylindrical body portion constituted of corrugated sheet metal, a base ring interfitting with the lower end of the body portion of the housing and adapted to be secured to and electrically grounded on a suitable foundation, a metallic roof for the upper end of the housing, the lower end of the tank being in spaced relation to the lower end of the housing and the body portion and the upper end of the tank being in spaced relation to the body portion and roof of the housing respectively, means for supporting said tank, said means having portions extending beneath said base ring thereby to provide a stack extending around and along the tank from the space within the housing below the tank to the space in the housing above the tank, and a cowl at the center of the roof coacting with the space above the tank and with the stack around the same to provide for the flow of air under the influence of natural draft from the outside into the space below the tank thence through the stack, through the space above the tank and the cowl to the atmosphere.

4. A bulk storage and dispensing apparatus for liquid fuels comprising an inner metallic tank including a cylindrical body portion and end heads secured and hermetically sealed to the cylindrical body portion, an outer metallic housing enclosing and surrounding the tank and made up of a cylindrical body portion of corrugated sheet metal disposed in spaced relation to the cylindrical body portion of the tank, a base interfitting with the lower end of the cylindrical body portion of the housing and adapted to be supported on and electrically grounded to a suitable foundation, a metallic roof for the upper end of the housing, the ends of the tank being disposed

in spaced relation to the ends of the housing, and the cylindrical body portion of the tank being disposed in spaced relation to the cylindrical body portion of the housing to provide a stack extending around and along the tank from the space below the tank to the space above the same, a supporting ring of angle iron formation having its vertical flange engaged with the crests of the inwardly directed corrugations of the cylindrical body portion of the housing, means for maintaining the supporting ring in supporting engagement with the lower end of the tank, the vertical flange of the supporting ring and the outwardly directed corrugations of the cylindrical body portion of the housing defining air inlets to said stack, and a cowl combined with the roof of the housing and in cooperative relation with the space within the housing above the tank and with the stack to provide for flow of air under the influence of natural draft from the space within the housing and below the tank through said air inlets to the stack, through the stack, and through the space above the housing and through the cowl to the atmosphere.

5. A bulk storage and dispensing apparatus for liquid fuels comprising an inner metallic re-

ceptacle for containing liquid fuel, an outer metallic housing enclosing and surrounding the tank and coacting therewith to provide a stack along and around the housing, a cowl at the upper end of the housing and in cooperative relation to the stack to provide for flow of air through the stack into the atmosphere under the influence of natural draft, a valved outlet connected to the bottom of the tank, a dispensing hose connected to said valved outlet, said outlet being swingable to open and closed positions by the swinging of said hose, said housing having a door extending the full height thereof for providing for access to said dispensing hose, said door when open providing for the extension of said hose and its consequent opening of said valved outlet to allow dispensing of liquid fuel from the tank, said hose being positionable in the stack when not in use and in such position closing the valved outlet, releasable fastening means for securing the door in closed position, said door when closed and when the hose is stored in the stack retaining the hose in stored position and maintaining the valved outlet closed.

CHRISTIAN L. HANSEN.
